(57) CLAIM

The ornamental design for a fitness wheel with light ring, as shown and described.

DESCRIPTION

FIG. 1 is a perspective view of a fitness wheel with light ring according to our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The portions of the fitness wheel with light ring shown in broken lines are for illustrative purposes only and form no part of the claimed design.

The dash-dash lines define the bounds of the claimed design and form no part thereof.

1 Claim, 7 Drawing Sheets
